ERNST CURT LOESCHE, OF BERLIN-LANKWITZ, GERMANY

GRINDING MILL

Application filed December 30, 1926, Serial No. 157,988, and in Germany December 31, 1925.

My invention relates to improvements in grinding mills, such as are used for grinding various materials such as rock, ore, cement, etc. More particularly my invention relates to mills comprising a rotary container in the form of a shallow bowl or dish adapted to receive the material to be ground, rollers or balls pressed on the surface of the said container and adapted to crush the material, and means for removing the material which has been reduced to the desired degree of fineness, such means consisting of a blower for producing a current of air adapted to separate the fine particles from the coarse particles, or a sieve. One of the objects of the improvements is to provide a mill of this type which is effective in operation, and by means of which the material is ground within a comparatively short period of time. With this object in view my invention consists in providing means for practically continuously removing the material being ground from the rotary container, separating the fine particles from the coarse particles, removing the fine particles and letting the coarse particles pass to a point or points below said rotary container, wherefrom the coarse particles are returned on the rotary container for being again ground. By thus rapidly removing the finer particles from the container the action of the rollers or balls on the coarse particles is more efficient, so that grinding is rapidly completed.

Other objects of the improvements will appear from the following description of the invention.

For the purpose of explaining the invention several examples embodying the same have been shown in the accompanying drawings, in which the same reference characters have been used in all the views to indicate corresponding parts. In said drawings,

Fig. 1 is a sectional elevation showing my improved mill, the separation of the fine particles being effected by means of a current of air,

Fig. 2 is a similar sectional elevation in which in addition to the parts shown in Fig. 1 means are provided for causing the current of air to act on the coarse material be-

ing returned to the rotary container for separating therefrom any residue of fine material which might be left within the material after the first or main separating operation,

Fig. 3 is a sectional view taken on the line 3—3 of Fig. 2, the rotary container and the crushing rollers being omitted.

Figs. 4 and 5 are sectional elevations showing other modifications,

Fig. 6 is a partial sectional elevation illustrating the operation of the scoops for returning the coarse material to the rotary container,

Fig. 7 is a top-plan view of the container shown in Fig. 6,

Fig. 8 is a sectional elevation taken on the line 8—8 of Fig. 6, and

Fig. 9 shows cross-sections taken on the lines I—I, II—II and III—III of Fig. 8.

In the example shown in Fig. 1 my improved grinding mill consists of a casing 1 having, at its side, an intake passage 2 for a current of air, and an outlet passage 3, the passage 2 being connected with a blower for producing a current of air. To the top end of a vertical shaft 4 mounted in bearings 5, 5 a container 6 in the form of a shallow bowl is keyed, which container is located within the casing 1 and is adapted to be acted upon by crushing rollers 7 mounted on rockers 8, springs 9 acting on the said rockers in a direction for pressing the rollers 7 on the surface of the container 6. The shaft 4 is adapted to be rotated by suitable gearing. To show what may be done, bevel gear wheels 10 and pulleys 11 are provided. The bottom of the casing 1 is provided with a chute 12 through which the coarse material is removed for being returned to the top face of the container, the said chute including a gate 13 for normally closing the same.

In the operation of the apparatus the material to be ground is thrown on the container 6 through the passage 3, and the container 6 is rapidly rotated by means of the gearing 10, 11. By centrifugal action the material gradually moves outwardly and upwardly and in position for being acted upon by the rollers 7. Thereafter the partly ground material including fine and coarse

particles is thrown outwardly and away from the container 6 and into a current of air flowing from the passage 2, through the annular passage provided between the circumference 5 of the container 6 and the wall of the casing 1, and the passage 3. The velocity of the said current is such that the particles of the material which have been reduced to the desired degree of fineness are carried along and removed from the mill, while the coarse particles fall downwardly in opposition to the said current of air and on the inclined walls or bottom of the casing 1, from whence they 10 are delivered through the chute 12. Suitable means are provided for returning the coarse 15 particles to the container 6.

It appears therefore that the material being ground is practically continuously held in motion, and that the fine material is immediately removed, so that there is only coarse material on the container 6, and the crushing action of the rollers 7 is not hampered by the loose material.

In Figs. 2 and 3 I have shown a modification 25 in which the fine particles are more thoroughly separated from the coarse material. As shown in the said figures, the mill comprises a cylindrical casing 15 divided by a horizontal partition 16 into an upper chamber 30 17 and a lower chamber 18. Above the partition 16 an intake pipe 19 opens into the chamber 17, and at the top of the casing 15 an outlet pipe 20 opens into the same. To the top end of a vertical shaft 21 a container 35 22 in the form of a shallow bowl is keyed, and the said shaft is adapted to be rapidly rotated by means of a bevel gearing 23 and a pulley 24. Through the side wall of the casing 15 a chute 25 is passed into the chamber 17 through which the material to be ground is delivered on the top face of the container 22. The top face of the container 22 is engaged by crushing rollers 26 mounted on rockers 27 (one of each only being shown) 40 45 acted upon by springs 28. The container 22 is smaller in diameter than the casing 15, so that an annular passage 29 is provided between the said parts. Below the said passage 50 conical and partly nested frusto-conical members 30 are provided which are spaced from each other at their adjacent bottom and top parts thus providing annular passages 31. The container 22 is provided with holes 32, and in continuation of the said holes scoops 55 33 are fixed to the bottom of the container 22, the said scoops extending forwardly in the direction of the rotary movement of the container 22 and being adapted, upon rotation of the container, to raise the material deposited on the inner portion of the partition 60 65 16. As appears from Fig. 3 the pipe 19 is disposed tangentially of the casing 15.

In the operation of the apparatus the bowl-shaped container 22 is rapidly rotated, a current of air is blown through the pipe 19,

and the material is delivered on the top face of the container 22 through the chute 25. By reason of the tangential direction of the pipe 19 the current of air flows around the conical rings 30 and the passage 29, so that it is operative all over the circumference of the container 22. A part of the air flows upwardly through the annular passage 29, as has been indicated by the arrows α . The remainder of the current of air flows through the annular 70 passages 31 and upwardly, as has been indicated by the arrows γ . The material to be ground is delivered on the top face of the container 22 through the chute 25, and it moves outwardly thereon by centrifugal action, so that it is exposed to the crushing action of the rollers 26. Thereafter the partly ground material is thrown outwardly and into the passage 29, in which the fine particles are carried away by the current of air, 85 while the coarser particles fall downwardly and into the conical chamber included by the conical rings 30. On the said conical rings the coarser particles slide downwardly and to the part near the hub of the container 22, 90 and as the material drops from one ring to the next one, it is exposed to the action of the current of air flowing through the passages 31, which current of air separates any fine particles which might have been left within 95 the material. The material collected at the bottom part of the conical chamber included between the rings 30 and near the hub of the container 22 is raised by the scoops 33 through the holes 32 and to the central part 100 of the container 22, so that it is again subjected by centrifugal force to the crushing action of the rollers 26, the said operation being repeated until the material has been reduced to the desired degree of fineness. 105

110
Thus, by causing the material to move through a continuous circuit from the top face of the container 22, the passage 29, the top faces of the rings 30, the scoops 33, and the holes 32, any fine particles are separated from the coarse particles, so that the crushing rollers 26 act only on coarse material. 110

In the examples so far described, the fine particles are separated from the material by a current of air. In Fig. 4 I have shown a modification, in which separation is effected by means of a sieve or sifter. As shown in the said figure the grinding mill consists of a casing 36 containing a sieve 37 having the form of a frustum of a cone. To the vertical shaft 38 a container 39 in the form of a shallow bowl is keyed, and the shaft is adapted to be rotated by bevel gear wheels 40 and pulleys 41. Through the top of the casing 36 a funnel 42 is passed, through which the material to be ground and the partly ground material are passed on the top face of the container 39. The construction of the crushing rollers 43 is similar to the one described above. From 115 120 125 130

the bottom of the casing 36 a chute 44 extends downwardly and with its bottom end into position for delivering the partly ground material into a trough 45, from which the 5 said material is removed by means of an elevator 46 adapted to deliver the material over a chute 47 into the funnel 42. At the bottom part of the casing 36 there are screw conveyers 48 by means of which the fine particles 10 are removed.

In the operation of the apparatus the material to be ground is delivered into the casing 36 and on the container 39 through the funnel 42. By centrifugal force the 15 material moves outwardly and into position for being crushed by the rollers 43. The ground material is thrown away from the container 39, and it slides downwardly on the sieve 37. The fine particles of the material pass through 20 the sieve and into the bottom part of the casing 36, from which they are removed by the conveyers 48. The coarse particles move through the chute 44 and into the trough 45, from which they are lifted by the 25 elevator 46 and returned onto the container 39 through the funnel 42.

The modification shown in Fig. 5 is similar to the one shown in Fig. 4, and the same letters of reference have been used to indicate 30 corresponding parts. But as distinguished from Fig. 4, the means for returning the partly ground material to the top face of the container 39 are in the form of scoops 50 forming the continuation of holes 35 51 made in the container 39.

The operation of the apparatus is substantially the same as that described with reference to Fig. 4. But the partly ground 40 material is returned on the top face of the container 39 by means of the scoops 50.

In Figs. 6 to 9 I have shown the construction of the scoops by means of which the partly ground material is returned to the top face of the rotary container. As shown, 45 the said container 55 is keyed to a rotary shaft 56, and the bottom 57 of the casing enclosing the container 55 is inclined downwardly and towards the shaft 56, so that the partly ground material thrown beyond the 50 periphery of the container 55 collects near the axis of the container 55. Below the holes 58 scoops 59 are screwed to the bottom of the container, which scoops extend forwardly in the direction of the rotation of the container 55, as is shown in Fig. 7 in which the 55 direction of the rotation has been indicated by an arrow α . The cross-sections I—I, II—II and III—III shown in Fig. 9 clearly indicate the form of the scoops.

While in describing the invention reference has been made to particular examples embodying the same I wish it to be understood that my invention is not limited to the constructions shown in the drawings, and

that various changes may be made in the general arrangement of the apparatus and the construction of its parts without departing from the invention.

What I claim is:—

1. A grinding mill, comprising a casing, a rotary bowl-shaped container mounted within said casing and having a diameter smaller than that of the casing so as to provide an annular passage around the same, crushing rollers engaging the top face of said container, means operative within said casing and around said container for separating the fine particles of the material from the partly ground coarse particles, means for causing the partly ground coarse particles of the material to collect below said container near the axis thereof, said container being formed near its axis with holes, and means for returning the coarse particles collected below the container through said holes to the top face of the container. 70 75 80 85

2. A grinding mill, comprising a casing, a rotary bowl-shaped container mounted within said casing and having a diameter smaller than that of the casing so as to provide an annular passage around the same, crushing rollers engaging the top face of said container, means operative within said casing and around said container for separating the fine particles of the material from the partly ground coarse particles, means for causing the partly ground coarse particles of the material to collect below said container near the axis thereof, said container being formed near its axis with holes, scoops fixed to the bottom side of said container and in continuation of the holes made therein and extending forwardly and downwardly therefrom into position for elevating the coarse particles collected below the container on the top face thereof, and means for removing the fine particles from the casing. 90 95 100 105

3. A grinding mill, comprising a cylindrical casing, a rotary bowl-shaped container mounted within said casing and having a diameter smaller than that of the casing so as to provide an annular passage around the same, crushing rollers engaging the top face of said container, means for producing a current of air upwardly through said passage, and means for returning the coarse particles of material thrown from said container to the top face and near the axis thereof. 110 115

4. A grinding mill, comprising a casing, a rotary bowl-shaped container mounted within said casing and having a diameter smaller than that of the casing so as to provide an annular passage around the same, crushing rollers engaging the top face of said container, a conical member below said container and composed of nested frusto-conical members having openings between the same, said conical member being in position for receiv- 120 125 130

ing the material delivered from said container, and means for causing a current of air through said openings and upwardly therefrom.

5 In testimony whereof I have affixed my signature.

ERNST CURT LOESCHE.
